SELECTIVE SIGNALING APPARATUS

Application filed July 6, 1926. Serial No. 120,763.

The invention relates in general to a selective signaling apparatus, and more especially to a controller responsive to a predetermined codal signal transmitted from a remote point and operating selectively under the control of such signal to initiate one or more operations as desired. In certain of its aspects the invention relates to a selector mechanism subject to control from a remote 5 point by radiant energy.

One object of the invention is to provide a selective signaling apparatus including a combined selector and distributor of a novel and advantageous character embodying a 15 series of selector elements which are presented in rapid succession to an operating means responsive to a predetermined codal signal in order that such elements may be operated in a predetermined combination.

Another object is to provide a controller having a series of individually movable selector elements adapted to be set in motion by the start impulse of a received signal, for continuous operation through a fixed cycle, 25 and signal-responsive operating means for moving said elements selectively during such cycle.

A further object is to provide a controller embodying two parts normally held against relative movement by a series of selector elements which when moved through a predetermined operating cycle are selectively operated in response to a preconcerted codal signal only, and render said parts operative to 35 actuate a switch or other device for controlling or initiating the operation of a desired mechanism or instrumentality.

Still another object is to provide a controller in which the selector elements are mounted in a rotary drum or carrier for movement successively into operative relation with an operating means for such elements, and in which the elements are operated by power derived from the rotation of the drum but under the control of a signal-responsive means.

Another object is to provide, in a selective signaling system means, for automatically compensating for slight variations in speed between sending and receiving mechanisms 50 of the start-stop type, to better insure a

proper operative relation between a series of elements and a member adapted to operate thereon successively in timed relation to the units of a codal signal transmitted by the sending mechanism.

A further object is to provide a selective receiver in which one unit of a signal combination may be received while the effect of the preceding unit of the signal is retained for the purpose of distribution.

A further object is to provide a combined selector and distributor having a rotary drum and a synchronous electromagnetic motor for operating said drum at a predetermined substantially constant speed.

Another object is to provide a receiving apparatus of novel and advantageous character which is responsive to a codal signal the units of which may be represented by fields of radiant energy.

Still another object is to provide a receiving apparatus responsive to intermittent fields of radiant energy and including a detector tube and electromagnetic means in circuit therewith so as to operate under the control of the received energy.

Another object is to provide a receiver of the start-stop type having a device adapted to rotate through a complete operating cycle in which a series of selector elements are to be operated in response to the units of a received signal, in combination with means providing in each operating cycle a plurality of control periods corresponding to the units of the received signal and of a definite duration determined by the operation of the rotary device itself and independently of the length of the received signal units.

A further object is to provide a receiver of the character just referred to, having means including a detector tube responsive to fields of radiant energy constituting the units of the signal, and wherein the means for determining the length of the control periods includes a means operating intermittently under the control of the rotating device, to discharge the grid of the tube.

A general object is to provide a construction for the controller and its operating means, which is relatively simple, so as to be

55

capable of being manufactured on an economical basis and which is efficient and reliable in its operation.

The number and character of the operations governed by my selective controller may obviously vary widely. For example, the invention is susceptible to use in controlling such mechanisms as telegraph and telephone apparatus, train despatch mechanisms, sub-marines, aeroplanes, and the like. In the present instance, I have illustrated and will hereinafter describe my invention in a form which is especially applicable to the control from a moving motor vehicle of a garage door operating mechanism.

In carrying out my invention I employ a controller in the form of a rotary drum composed of two sections mounted for a limited relative rotational movement. The two sections are normally locked together by a series of selector elements in the form of axially slidable pins which, when operated in a preconcerted combination, release or unlock the two sections for relative movement. The drum is started under the control of electromagnetic means and is driven through a predetermined operating cycle (one revolution) at a substantially constant speed and in substantial synchronism with an apparatus for sending a codal signal corresponding to the combination to be selected. Thus, the sending apparatus also operates through a predetermined cycle, being started in the present instance under manual control. The sending and receiving apparatus, therefore, are in the nature of start-stop mechanisms, the receiver having means operating in response to the successive units of a transmitted signal to control the selection of a predetermined combination of elements.

Near the end of the operating cycle of the drum, the two sections thereof are caused to move relative to each other as permitted by the operation of the selector elements in the predetermined combination, and such relative movement is utilized to operate a switch or other control device. The selector elements are operated under the control of the received signal but by power derived from the rotation of the controller drum.

Associated with the controller, in the present instance, is an apparatus adapted for the reception of intermittent fields or wave trains of electromagnetic energy, which together with the intervening spaces constitute the units of the codal signal. This receiving apparatus includes an antenna and a detector tube, with an electromagnetic means in the plate circuit of the tube operated in response to variations in the current in such circuit to start the controller and govern the selector-operating means. In order that the units of the signals may be transmitted and received in close succession, means is provided to dis-

charge the grid of the tube periodically once for each such unit of the signal.

Referring now to the accompanying drawings:

Figure 1 is an elevational view looking toward one end of the device. 70

Fig. 2 is a fragmentary view illustrating the electromagnetic synchronous motor for operating the rotary drum.

Fig. 3 is a fragmentary elevation of the 75 rotary drum and the means operating under the control of the received codal signal for actuating the pins of the drum.

Fig. 4 is an elevational view of the end of the device opposite that shown in Fig. 1, 80 the detector tube being omitted.

Fig. 5 is a horizontal plan section illustrating more especially the pin drum and the means for pushing the pins under the control of the electromagnetic means. 85

Fig. 6 is a fragmentary sectional view through a portion of the drum and illustrating a detail of construction.

Figs. 7 and 8 are views partially schematic in character, showing the arrangement of the pins in the drum and illustrating the manner in which the pins in the drum constitute a combination device operable only by a signal transmitted in accordance with the predetermined code. 90

Figs. 9 and 10 are detail sectional views illustrating the means employed for restoring the relatively movable parts of the drum to their initial positions.

Fig. 11 is a view partially schematic in character illustrating the relation between the means for pushing the pins and the means for discharging the grid of the detector tube. 100

Figs. 12 and 13 are perspective views illustrating the operation of the switch by the pin drum. 105

Figs. 14 to 17 inclusive are schematic views illustrating more especially the arrangement for discharging the grid to render the magnetic field produced by the stopping of the synchronous motor ineffective. 110

Fig. 18 is a front elevational view of the device, a portion being broken away and part shown in section to illustrate details of construction. 115

Fig. 19 is a view of the several contacts operated under the control of the pin drum to initiate the several operations desired.

Fig. 20 is a wiring diagram of the receiving apparatus including diagrammatic illustrations of certain of the operating parts. 120

Fig. 21 illustrates similarly a transmitting apparatus.

Fig. 22 is a plan view of the transmitter. 125
The control device, as above indicated, is in the present instance in the form of a drum indicated generally by the numeral 1. This drum is made in two sections, (Figs. 5, 7 and 8) one of which comprises a disk 2 and the 130

other of which comprises a pair of disks 3 and 4 spaced some distance apart. The three disks are mounted upon a shaft 5 so that the two sections of the drum are capable of a limited relative rotational movement for the purpose of operating an electric switch 5^a (Figs. 12 and 13) as will be presently described. Herein the disk 2 is loose upon the shaft and the disks 3 and 4 are fast.

10 The two sections of the drum are normally held or locked together by means of selector elements in the form of axially slid able bars or pins 6 arranged near the periphery of the drum in a circular series and in spaced relation. Of these pins 6 there are in the present instance eleven, and in addition the drum carries a plurality of auxiliary control pins (herein three) designated respectively by the numerals 7, 8 and 9. Initially each of the pins 15 is set by a reset device or cam 10 formed on a stationary disk 11 located at one end of the drum, this cam being positioned so as to reset each pin before it is presented to a pin pushing or actuating means 12 which constitutes 20 the distributor for the units of the received signal.

The pins 6 are of equal length but are formed in two sections (Fig. 7) so arranged that the dividing lines in the case of certain 25 of the pins are initially located within the disk 2, and when pushed are located between the disks 2 and 3. In the case of the other pins, the dividing lines are initially located between the disks 2 and 3, and if these pins are pushed, 30 said lines will be positioned within the disk 3. Thus, it will be seen that the pins of the first group must, in the rotation of the drum, be pushed to position their dividing lines between the disks 2 and 3, in order to permit 35 relative rotation between the two sections of the drum; and on the other hand the pins which have their dividing lines initially located between the two disks 2 and 3 must not be pushed, for if they are, their division 40 lines will fall within the disk 3 (Fig. 8), and thus they will serve to lock the disks against 45 relative rotation. The arrangement is such, therefore, that the pins which have their dividing lines offset with respect to the space 50 between the two sections of the drum are those which must be operated in accordance with the prearranged plan, and only such pins must be operated in order to permit relative movement between the disks 2 and 3.

55 The pins 7, 8 and 9 are non-sectional in character and respectively carry collars 7', 8' and 9' which, as will be hereinafter more fully set forth, are adapted to operate one 60 or more auxiliary switches. As shown in Figs. 7, 8, 12 and 13, the pins 7, 8 and 9 project through an arcuate slot 13 in the disk 2, so as to permit relative rotation between 65 the two sections of the drum. Such relative rotation is limited by a pin and slot connec-

tion 13^a (Figs. 4 and 9) between the disks 2 and 3 of the drum.

The shaft 5 carrying the drum, is journaled in suitable standards 14 and 15 rising from a base plate 16, these standards being 70 spaced apart to receive the drum between them.

The drum is arranged to be rotated by suitable means comprising, in the present instance, a synchronous electromagnetic motor 75 including an electromagnet 17 having an armature 18. The magnet 17 is mounted upon a horizontal arm 19 secured upon the upper end of an upright frame member 20 rising from the rear side of the base 16; and the armature 18 is mounted upon a pair of spaced resilient arms 21 securely clamped in a fixed shaft 22 supported at opposite ends in depending brackets 23. As shown in Figs. 2 and 4, this fixed shaft 22 is cut to form a removable section 24 which is fastened to the shaft proper by means of bolts 25, with the rear ends of the spring arms 21 clamped between the two parts of the shaft.

The magnet 17 is arranged to be energized 90 in the present instance, from a source of alternating current, and the magnet, responding to the alternations in current occurring twice per cycle, rapidly raises and lowers a spring pawl 26 depending from the armature 18. 95 Said pawl 26 is adapted to engage with a ratchet wheel 27 fast upon a shaft 28 supported at its opposite ends in a pair of bracket arms 29 secured to opposite sides of the standard or post 15. The shaft 28 carries a worm 100 30 meshing with a worm wheel 31 (Fig. 18) which is fast upon the shaft 5, the latter being extended beyond the post 15. A spring retaining pawl 32 coacts with the ratchet wheel upon the side opposite the pawl 26 to prevent 105 reverse rotation. It has been found that with this arrangement the shaft 5 may be rotated at a substantially constant speed due to the fact that the alternating current supply is, according to present practice, maintained at a 110 substantially constant frequency.

Moreover, it has been found that the magnet 17, together with the means for effecting rotation of the shaft 5 when the magnet is energized, constitutes a vibratory electric motor 115 which is adapted to attain its normal torque and speed substantially instantaneously, and which is therefore especially adapted for driving the rotary carrier for the selector elements under conditions where the motor must be started and stopped at the beginning and end of each operating cycle.

Suitable means is employed, as hereinafter set forth, for controlling the operation of the magnet 17 so as to effect rotation of the shaft 125 5 and hence of the pin drum 1 through one revolution or operating cycle. In such rotation the pins in the drum are successively moved into position relative to the distributor 12.

The distributor 12 is preferably of such a character that it is merely controlled by the codal signal, the power for pushing the pins being derived from the rotation of the shaft by the synchronous electromagnetic motor 17, 18. To this end said distributor comprises a pivoted member 33 which may be termed a plow, and which is mounted so as to be disposed normally in the path of the projecting ends of the pins. This plow 33 (Fig. 5) is in the form of a metallic finger pivoted at one end as at 34, and having at its other end a bent portion 35 which is normally held by a light coiled spring 36 in the path of rotation of the projecting ends of the pins. A combined guide and stop member 37 serves to limit the movement of the plow by the spring.

The pins are frictionally held in the drum so as to tend to resist movement by engagement with the plow, and the arrangement is such that unless the plow is restrained from pivotal movement upon being engaged by a pin, the spring 36 will permit it to yield without imparting a movement to the pin. The means for frictionally holding the pins against movement may be of any suitable character, that herein shown comprising in each instance (Fig. 6) a radial socket 38 in each of the disks 2 and 3, in which is seated a coiled expansion spring 39 operating to force a ball 40 into frictional engagement with the pin passing transversely of the outer end of the socket.

The means for controlling the plow 33 so as to effect the movement of the desired pins, comprises a control figure 41 arranged to coact with a fixed stop member 42 (Figs. 3 and 4) and a coating lug 43 carried by the plow but disposed so as to be capable of moving beneath the stop 42 when unrestrained by the control finger. According to the arrangement employed in the present instance, the finger 41 is normally positioned in interlocking relation to the stops 42 and 43 (see Fig. 3). Thus, when a pin is to be operated, the plow is prevented from yielding and the plow acting as a cam moves the pin by power derived from the rotation of the drum.

The interlocking finger 41 is in the form of an upstanding flange (Fig. 5) on the rear end of a lever arm 44, the forward end of which carries the armature 45 of a relay 46. The lever arm 44 is pivoted between its ends as at 47, between a pair of depending bracket arms 48. The upper ends of these arms are secured upon opposite sides of a bar 49 which carries, at its forward end, the coils of the relay 46.

In the present instance the relay 46 is normally energized during the operating cycle, and is operated upon a decrease in the current flowing through the circuit in which it is interposed, as will be hereinafter described. A spring 50 (Figs. 1 and 18) is anchored at its upper end, as at 51, to the bar 49, and at

its lower end to the arm 44 at a point rearwardly of the fulcrum 47 of the arm. The spring thus tends to lift the rear end of the arm, but the strength of the spring is such as to be unable to overcome the normal attractive force of the relay.

The interlocking finger 41 is thus movable, under the control of the relay 46, into and out of position between the lug 43 on the plow and the stationary stop 42. When the armature is attracted by the relay, the finger blocks the plow so as to push a pin, and when the armature is released the finger is raised into a position above the movable stop 43, thus permitting the plow to yield laterally against the action of the spring 36 (see Fig. 11). Under such a condition, therefore, the finger is held against downward movement by the stop 43 and a pin is not operated.

It will be seen that as the shaft 5 is rotated by the operation of the electromagnetic motor 17, 18, the pins in the drum are presented in rapid succession to the operating device 12, and that the pins are pushed depending upon whether or not the plow is prevented from yielding laterally by the movement of the interlocking finger 41 under the control of the signal-responsive relay 46. The units of the signal are thus in effect distributed so as to control the selection of the predetermined combination of pins in the controller drum; and it will be observed that as an incident to the engagement of the plow with any one of the pins, the effect of the signal unit which is to be transferred to that pin is retained until the pin passes out of engagement with the plow. The signal responsive magnet, however, is free to respond to the next unit of the signal combination in advance of the disengagement of the plow from the said pin. Thus the period during which the magnet is responding to one signal unit may overlap the period during which the preceding unit is being distributed. The manner in which a signal unit received during the overlapping period is timed to effect the control of the plow for that period is hereinafter set forth in connection with the description of the radiant energy detector.

Assuming that the pins 6 occupy the relative positions shown in Fig. 8 at the end of an operating cycle of the drum, it will be apparent that relative rotational movement between the two sections of the drum is permissible, owing to the fact that the dividing lines between the sectional pins are all located between the disk 2 of one section and the disk 3 of the other section. I utilize such relative movement for the purpose of operating a control device such as a switch which in turn is adapted to control the desired operating mechanism, such, for example, as a door operating mechanism. To this end I provide on the disks 2 and 3, respectively, peripheral lugs 52 and 53 (Figs. 12 and 13) arranged to

coact with rollers 54 and 55 mounted on the ends of a pair of spring arms 56 and 57 respectively. The arms 56 and 57 are inclined in an upward and rearward direction as shown in Fig. 4, being suitably fastened at their lower ends upon a block 58 of insulation material. The arm 56 carries at its upper end a laterally extending finger 59 carrying a contact 60 which is arranged to overlie the contact 61 on the upper end of the arm 57. The rollers 54 and 55 engage yieldably with the peripheries of the disk 2 and 3, and the construction is such that the two lugs engage with their respective rollers simultaneously in the normal or locked relation of the two disks. The roller 54, however, is adapted upon engagement with the lug 52 to interpose sufficient resistance to the rotation of the disk 2 (the latter being loose on the shaft) to interrupt or retard the rotation of the disk 2 for a brief interval while the disk 3 continues to rotate. As a result, the arm 57 is in this operation elevated in advance of the arm 56 so as to carry the contact 61 into engagement with the contact 60 and thus close the switch formed by these two contacts. If, however, the pins 6 have not been properly set to permit such relative rotation between the two disks, both lugs 52 and 53 simultaneously engage and move their rollers 54 and 55 (Fig. 13) thus maintaining the contacts 60 and 61 in spaced relation and preventing closing of the switch.

The pins 7, 8 and 9 may or may not be pushed in the rotative cycle of the drum depending upon whether or not the codal signal has included therein units intended to effect the operations controlled by these pins. Herein the pins 7 and 8 with their collars 7' and 8', are arranged to control respectively two sets of switch contacts 62 and 63 (Fig. 19); and the pin 9, with its collar 9' is arranged to control two sets of contacts 64 and 65. As herein shown, each set of contacts 62 and 63, and 64 and 65, comprises a relatively stationary contact and a movable contact. The movable contacts in each case are mounted on suitable spring arms 66, and carry rollers 67 and 67^a, and 68 and 68^a. The rollers 67 and 67^a are adapted to be engaged selectively by the collar 9' on the pin 9, and the rollers 68 and 68^a are arranged to be engaged selectively by the collars 7' and 8' on the pins 7 and 8.

It will be obvious that the switch mechanism which is thus arranged to be actuated selectively in the operation of the controller, may vary in construction and arrangement, as desired. When applied to the control of garage doors, the switch contacts 60 and 61 may serve to control the operation of the motor circuit, while one set of auxiliary switch contacts may govern the selection of one of two sets of doors, and the other set, the operation of the garage lighting system, all as

set forth in a copending application of Duncan J. Stewart, Serial No. 177,555, filed March 23, 1927.

To reset the two sections of the pin drum at the end of each operating cycle, I employ the device shown in Figs. 9 and 10, which provides the pin and slot connection 13^a for limiting the extent of relative movement between the drum sections. This device comprises a pin 69 passing through both sections of the drum and carrying a cylindrical head 69^a slidable through the disk 3. Said head has a conically tapered end arranged to enter a complementary seat 69^b in the disk 2 under the action of a coiled expansion spring 69^c. A slot 69^d is formed in the disk 2 to receive the outer end of the pin 69, but this slot is located slightly off-center with respect to the conical seat 69^b. Near the end of the operating cycle of the pin drum, the pin 69 is adapted to engage with a stationary cam member 69^e to operate the pin 69 against the action of its spring 69^c, thus removing the head 69^a from its seat (Fig. 10). The pin 69 is now free to move in its slot 69^d so as to permit relative movement between the disks 2 and 3 while the pin moves with the disk 3 from one side of the slot 69^d to the other. Thereupon the pin is disengaged from the cam member 69^e and the spring 69^c operates to reseat the head 69^a in its seat to restore the disks 2 and 3 to their normal relation (Fig. 9).

As first above indicated the means for selectively operating the pins of the controller may be responsive to various forms of transmitted energy, including line current impulses and radiant energy in its various forms. In the present embodiment the pin operating means 12 is responsive to a codal signal, the units of which are formed by the intermittent transmission of electromagnetic induction fields. The use of this form of energy is preferable when possible in connection with remote control systems for the reason that such fields being limited in extent of range present little or no difficulties from the standpoint of interference with radio communication. On the other hand, where the distance to be covered is relatively great, fields produced by Hertzian waves may be preferred.

Referring now to Figs. 21 and 22, I have shown diagrammatically a transmitting apparatus such as may be employed in the transmission of intermittent induction fields from a motor vehicle, and I have shown diagrammatically in Fig. 20 a receiving apparatus embodying my controller.

Referring first to the apparatus shown in Figs. 21 and 22, the sending means may comprise one or more sending disks (herein two) 70 and 70' arranged to operate through successive cycles to close switches 71 and 71'. 125

The former is interposed in a circuit 72 including a battery 73 (which may be the storage battery of a motor vehicle) and the primary 74 of an induction coil 75 having the usual vibrator 76. A spark gap 77 is connected across the secondary 74^a of the coil 75 and in series with a coil or loop aerial 78 which may be mounted beneath one of the running boards of a motor vehicle. A condenser 79 is interposed in the loop or oscillation circuit. The switch 71' is interposed in a circuit 80 in shunt with the circuit 72 and including a part of a lighting circuit 81 of the motor vehicle, the latter circuit having therein the usual hand operated switch 82.

The switches 71 and 71' are adapted to be closed in each operating cycle, the disks 70 and 70' controlling said switches being constructed to provide peripheral depressions 83 and elevations 83^a constituting control elements adapted to determine the character of the units of the signal. A follower 84 coacts with the periphery of the disk 70 so as to close the switch contacts of the switch 71 intermittently, and the disk 70', which has in the present instance a single elevation, has a follower 86 to close the switch 71' once for each cycle of operation. It will be evident, therefore, that in each cycle of operation of the disks 70 and 70', switches 71 and 71' are operated, the former operating intermittently at predetermined intervals and the latter operating once in each cycle but in a predetermined relation to the operation of the switch 71 by the disk 70, these two disks being fast on a shaft 87. Where two elevations 83^a occur in succession, they may be combined as indicated at 85 (Fig. 21).

Suitable means is of course provided for rotating the disks 70, 71 through successive cycles. This means generally stated may comprise an electromagnetic motor including an electromagnet 88, in circuit with the battery 73, and a pawl and ratchet mechanism 89. This motor is arranged to be started by a hand operated switch 90 and stopped by a switch 91 which is controlled by a disk 92 on the shaft 87. The flow of current to the magnet is controlled by an interrupter 93; and power is transmitted to the shaft 87 through a spring (not shown) in which energy is stored during each operating cycle for use in starting the succeeding operation. 94 (Fig. 22) designates generally a starting device tripped by the magnet 88 upon the closing of the switch 90, and 95 is an escapement mechanism operating to maintain the speed of the shaft 87 substantially constant. Inasmuch as the transmitting mechanism per se forms no part of the present invention, it is deemed unnecessary to illustrate and describe the same in detail, reference being made, for a complete disclosure, to my copending application Serial No. 175,377; filed March 14, 1927.

It will be understood from the foregoing brief description, however, that subject to the operation of the switch 90 to start the driving mechanism, and the switch 82 controlling the car lighting system, intermittent induction fields will radiate from the oscillation loop 78, these fields occurring at predetermined intervals corresponding to the spacing of the pins in the controller which are not to be operated. In this connection, it will be remembered, the controller is so arranged that the pin operating means is normally adapted to operate the pins in the rotation of the drum.

Referring now to Fig. 20, the receiving apparatus comprises a grounded antenna 98 which is coupled at 99 with a controlling circuit 100 containing a vacuum detector tube 101 and a fixed condenser 102. A variable condenser 103 is preferably connected across the secondary of the inductive coupling 99.

The tube 101 may in practice be mounted on a bracket 101^a (Fig. 1) carrying a socket 101b. As shown in Fig. 20, the tube is of the three element type, including a control element or grid 104, an anode or plate 105 and a cathode or filament 106. The filament has a variable resistance 107 in series therewith, and is heated continually from a 110 volt A. C. line through a transformer 108 stepping down the voltage to approximately six volts.

The current in the plate or controlled circuit 109 is unidirectional in character while the applied voltage is alternating in character. Thus, it will be observed that the antenna circuit is untuned and that the tube input circuit is tuned by the variable condenser 103. Detection is effected by the grid condenser method, no grid leak being employed for reasons which will appear later.

In said plate circuit is interposed electromagnetic means (in the present instance the relay 46) which is in shunt with a condenser 110. The armature 45 of the relay 46 carries the movable contact of a switch 111 which controls a circuit 112, 118, containing the electromagnet 17. This magnet 17, it will be remembered, constitutes the synchronous electro-magnetic motor which operates to drive the drum shaft 5.

On the shaft 5 is a disk 113 (Figs. 18 and 20) having a notch 114 in its periphery adapted to receive a follower 115 carried by the movable arm 116 of a switch 117. Said switch 117 in parallel with switch 111 also controls a circuit 118 including the motor magnet 17, the arrangement being such that when the circuit 112 is initially closed by the switch 111, the motor magnet is operated to drive the drum shaft 5 and thereby the controlling cam disk 113 so as to close the switch 117. The latter switch thus assumes control so as to relieve the switch 111 controlled by the armature 45, the circuit 118 through the motor magnet being opened by the operation

of the switch 117 at the end of one complete revolution.

It will be seen that the relay 46 in the plate or controlled circuit 109 is normally energized so that the switch 111 is normally open. The received wave trains affect the grid in the well known grid condenser method, producing a negative charge thereon, which results in a decrease in the current in the plate circuit 109 and a consequent release of the relay armature, thus closing the switch 111. Initially, the relay is operated in response to a wave train propagated under the control of a tooth 111^a on the sending disk 70, this tooth being located in advance of the signal controlling elements 83, 83^a; and such initial operation, acts through the switch 111 to start the synchronous driving motor 17, 18. The normal flow of current through the relay is restored periodically to energize the relay, by means to be presently described for discharging the accumulated charge on the grid. The manner in which the relay operates to control the operation of the selector elements or pins in the pin drum has been described above. The condenser 110 in parallel with the relay 46 alternately becomes charged and discharges, and thus effects a smoothing out of the wave, which prevents the relay from chattering.

The means for periodically discharging the grid or controlling circuit of the receiving apparatus, to effect a restoration of the normal flow of current through the plate or controlled circuit, comprises in the present instance a disk 119 (Fig. 20) also mounted on the shaft 5. This disk has formed on its periphery a series of teeth 120 one for each of the series of pins 6, as well as the pins 7, 8 and 9, of the pin drum. Moreover, the spacing of the teeth is such as to correspond to the spacing of the pins in the drum (see Figs. 7 and 8). Thus in the present instance the first eight teeth are spaced a relatively short interval apart, as is the case of the pins 1 to 8 of the drum, and the remaining teeth are spaced a relatively larger distance apart as is the case with the pins 9 to 14 inclusive of the drum.

Coacting with the disk 120 is a follower 121 on the movable arm of a switch 122, one side of which is connected to the grid by a conductor 123, and the other side of which is connected to a point whose potential is approximately equal to the potential of the filament or positive thereto. As herein shown it is connected by a conductor 124 to the grounded side of the filament circuit. It will thus be apparent that in the rotation of the disk 120, the grid is periodically discharged once for each of the selector elements in the pin drum.

Referring now to Fig. 11, the timing of the discharge in relation to the movement of the pins relative to the plow 33 will be ap-

parent. Thus, it will be seen that the discharge switch 122 is closed just subsequent to the engagement of a pin with the plow 33, so that if the relay has been operated by a signal unit so as to effect the release of the armature 45, the lug 43 on the plow will clear the interlocking or control finger 41, which has moved upwardly from the position shown in Fig. 3, with the operation of the relay; and on the other hand, if the relay has not been operated under the control of the received signal, the plow will be blocked by the finger 41 and hence will operate the pin engaging therewith. In either event, the grid will be discharged immediately after the presentation of a pin to the plow so as to insure that the grid is restored to its normal condition, thus enabling it to respond to the succeeding unit of the signal if the plow is to be blocked to effect the operation of the next pin. In other words, at a point in the operating cycle just subsequent to the engagement of the plow 33 by a pin in the drum, the corresponding tooth 120 on the disk 119 operates to close the switch 122 and discharge the grid. Thus the effective control period during which a signal unit may be received to control the operation of the plow for a given pin, commences with the discharge of the grid at a fixed point after the engagement of the plow by the preceding pin, and ends with the engagement of the plow by the given pin. It is noted in this connection that in the event that the plow has been blocked by the interlocking finger 41, the pressure of the lug 43 against the finger 41 (Fig. 3) is sufficient to hold the finger down. This is true notwithstanding the restoration of the flow of current through the relay by the discharge of the grid, which restoration follows immediately after the engagement of the plow with the finger. As shown in said Fig. 3, the lower edge of the finger may be bent slightly as indicated at 125 and the end of the lug 43 correspondingly shaped to insure the maintenance of this holding engagement between the finger and the lug.

It will now be apparent that in the operation of the sending mechanism through one operating cycle, a codal signal is transmitted having a series of units which, in the present instance, are formed by intermittent fields of electromagnetic energy and the intervening spaces in accordance with the arrangement of the elements 83, 83^a on the sending disks 70 and 70'. After the initial operation of the relay to start the controller, the circuit 118, also containing the motor magnet, is completed by the closing of the switch 117. In the ensuing rotation of the pin drum, the pins are successively presented to the plow 33 and are pushed or not pushed depending upon the character of the signal units as determined by the controlling elements 83, 83^a on the send-

ing disks 70 and 70'. At the end of this cycle, the drum is stopped by the opening of the switch 117 under the control of the cam disk 113.

5 It will thus be apparent that in order to effect the operation of the proper selector elements to unlock the disks 2 and 3 of the drum for relative movement, the sender and receiver must operate in substantial synchronism. 10 In order, however, to increase the allowable speed variations between the driving means for the transmitter and the driving means for the receiver, I provide a greater space between the pins in the drum near the end of 15 the series as compared to those at the beginning of the series, and a corresponding spacing of the control elements 83, 83^a on the sending disks 70, 70'. Each of the units of 20 the signal, however, as produced by the elements 83, 83^a are of the same duration. Thus a prolonged operating period is provided for each of the latter pins of the series. In order 25 that the grid discharge means shall correspond to such spacing of the pins in the drum and of the signal units, I provide an increased spacing of the latter portion of the teeth 120 on the grid discharge disk 119. This arrangement will be apparent from a 30 comparison of the arrangement of the pins shown in Figs. 7 and 8 with the arrangement of the elements 83, 83^a on the sending disks and the teeth 120 on the grid discharge wheel shown in Fig. 20. In each instance, the spacing employed at the end of the series is 35 substantially greater than that employed at the beginning of the series. The result is that the interval of time during which the plow is adapted to be controlled by the finger 41 is prolonged in the case of each of the pins near 40 the end of the series.

In order that variation in the speeds of the sending and receiving mechanisms may occur in either direction, the spacing of the pins must be such as to be presented to the plow 45 substantially at the central point in the enlarged pin operating period. To illustrate clearly the relative spacing of the pins in the controller drum and of the control elements 50 on the sending disks 70, 70', I have in Fig. 20 indicated by small figures the numbers of the pins of the series, and in Fig. 8 I have shown a combined development of the two sending disks 70 and 70' and similarly indicated the numbers of the corresponding controlling 55 elements on the sending wheels. While in practice two elevations occurring in succession on the sending wheel are combined as above set forth and as shown in Fig. 21, I have in Fig. 8 shown the elevations and depressions individually.

60 Referring now to Figs. 14 to 17 inclusive, I have found that as a result of the opening of the switch 117 under the control of the cam disk 113 at the end of the operating cycle, and the consequent interruption of the flow of

current to the motor magnet 17, an induction field is created which is sufficient to effect a variation of the current in the plate circuit and thus cause the relay 46 to start the controller. In order to insure that the tube shall not be affected in this manner, I provide means operating near the end of the cycle to continue the discharge of the grid until after the switch 117 has been opened. This means comprises, in the present instance, a segmental weight 126 (see also Fig. 18) loosely mounted 70 on the shaft 5 of the controller between the grid discharge wheel or disk 119 and the cam disk 113. Also mounted on the shaft 5 and rigid therewith is a disk 127 (Fig. 18) having a pin 128 therein entering a slot 129 in the grid discharge wheel 119, the latter being loose on the shaft. The weight 126 has a pin 130 therein which projects laterally into an elongated slot 131 in the cam disk 113. 80

85 In Fig. 14 the parts are shown in the relation which they occupy after the controller has operated through slightly more than a half cycle. Obviously the weight 126 is being carried upwardly by the engagement of the pin 130 on the weight with the trailing end of the slot 131 in the cam disk 113. In Fig. 15 the parts are shown near the end of the cycle. Thus the weight 126 has been carried by the disk 113, into its uppermost position, and then 90 slightly beyond through the action of gravity, until stopped by a laterally projecting lug 132 on the weight 126 which engages with a laterally extending stop finger 133 (Fig. 18) on the movable contact arm of the switch 117. 95 At this time the movable contact of the grid discharge switch 122 is raised by an elongated tooth or segment 134 on the grid discharge wheel 119, the latter being held back by friction between the tooth 134 and the follower 100 105 110 115 120 125 130

121 In the continued operation of the motor magnet 17, the notch 114 in the controlling cam disk 113 becomes positioned (Fig. 16) so as to receive the follower 115 of the movable contact of the switch 117, thus opening the switch 117; but the follower 121 of the switch 122 continues to be held raised by the elongated tooth or segment 134 (Fig. 16). In such movement of the follower 115 into the notch 114, the stop finger 133 moves downwardly out of the path of the lug 132, so that the weight 126 is now free to fall by the action of gravity, as permitted by the elongated slot 131, until it strikes a pin 135 projecting laterally from the grid discharge wheel 119. 120 The force of the impact operates to move the grid discharge wheel as permitted by the slot 129, so as to move the elongated tooth or segment 134 from beneath the follower 121 of the grid discharge switch 122 (Fig. 17).

125 Thus, it will be evident that by the construction provided, the final discharge of the grid is prolonged until after the opening of the circuit to the motor magnet, whereupon the grid discharge means is moved to its initial 130

or normal position so as to restore the tube 101 for the reception of the next signal.

While I have herein illustrated and described my invention with considerable particularity, it is contemplated that various changes in the construction and arrangement employed may be made by those skilled in the art without departing from the spirit and scope of the invention as expressed in the appended claims. I desire to have it expressly understood that the selective controller is not limited to use with a receiving apparatus responsive to radiant energy, for obviously the controlling codal signal may be represented by electric current impulses transmitted over a wire. On the other hand, I have employed the term "radiant energy" in a generic sense, as including the various forms of energy which exist in or travel through space, such, for example, as electrostatic energy, Hertzian waves, sound and light.

Moreover it should be understood that while I have herein illustrated and described a vacuum tube as the means responsive to the transmitted radiant energy fields, I do not intend to be limited to such a device, it being obvious that any other thermionic device may be employed as an equivalent element.

30 The vibratory motor, not herein claimed per se, is made the subject of a copending application filed February 15, 1929, as Serial No. 340,217, by myself and Duncan J. Stewart, jointly.

25 I claim as my invention:

1. A controller of the character described comprising, in combination, a drum having a series of individually movable selector elements arranged in circular series, a signal-responsive operating device, drive means for rotating said drum, means momentarily operative under the control of said signal responsive means to start the driving means, said driving means being operable when once 45 started to carry all of said elements in rapid succession into operative association with said device for selective operation thereby whereby a predetermined combination of said elements are operated, and a control device operable upon the selection of such combination of elements.

2. A controller of the character described comprising, in combination, a drum formed in two sections and having a plurality of 50 selector elements arranged in circular series and normally locking said two sections together, signal-responsive means for operating a predetermined combination in said elements, said elements being operated in such combination to release the two sections of the drum for relative movement, and a control device operated in such relative movement between the two sections of the drum.

3. A controller of the character described 55 having, in combination, a plurality of selec-

tor elements and a rotary carrier therefor, and means for operating said elements selectively including a member yieldably held in the path of movement of the selector elements, and signal-responsive means adapted to hold said member against yielding or permit yielding thereof according to the character of the received signal. 70

4. A controller of the character described having, in combination, a plurality of selector elements and a rotary carrier therefor, and means for operating said elements selectively including a member yieldably held in the path of movement of the selector elements, and means positioned to prevent said 80 member from yielding but movable into another position out of holding relation to said member. 75

5. A controller of the character described comprising, in combination, a plurality of selector elements, a carrier in which said elements are arranged in spaced relation, a device for operating said elements, means for effecting relative movement between said elements and the operating device, said operating device comprising a member having an actuating surface normally disposed in the path of the elements successively presented thereto, said member being mounted so as to be capable of yielding out of operative relation to said elements, and selectively operable means for holding said member against yielding to effect movement of the engaged element out of normal 90 position. 85

6. A controller of the character described comprising, in combination, a plurality of selector elements, a carrier for said elements, and means for operating said elements selectively comprising a member adapted when held in an operating position in the path of said elements to move them relative to the carrier, said member being movable out of said operating position, a stop, and a signal-responsive device operable to move relative 100 to said member and said stop whereby to hold said member in its operating position. 105

7. A controller of the character described comprising, in combination, a plurality of selector elements, a carrier for said elements, an operating member for said elements, means for effecting relative movement between said member and the carrier to present said elements successively to said operating member, a stop, and a signal-responsive device including a finger movable into and out of interlocking relation with said stop and said member whereby the stop becomes effective to prevent movement of the member when the latter is engaged by one of said 110 elements. 115

8. A controller of the character described comprising, in combination, a plurality of selector elements, a carrier for said elements, an operating member for said elements, means 120

125

130

- 5 operating to present said elements successively to said operating member, a stop, and a signal-responsive device for rendering said operating member effective or ineffective including a finger movable into and out of interlocking relation with said stop and said member, said signal responsive means including a relay having an armature adapted to move said finger.

10 9. A controller of the character described comprising a drum formed in two sections and having a plurality of selector pins mounted thereon and normally locking said two sections of the drum together, means for operating said pins selectively, said pins being adapted when operated in a predetermined combination to release the two sections of the drum for relative movement, a device normally operating to prevent relative movement between said two sections, and means operable at a predetermined point in the rotation of the drum to render the said device ineffective.

15 10. A controller of the character described comprising a drum formed in two sections and having a plurality of selector pins mounted thereon and normally locking said two sections of the drum together, means for operating said pins selectively, said pins being adapted when operated in a predetermined combination to release the two sections of the drum for relative movement, and a device operable at a predetermined point in the rotation of the drum to permit a limited relative movement between said two drum sections, said device being subsequently operable to reset the two sections of the drum in their normal relation.

20 11. In a controller of the character described, a drum formed in two sections and having a plurality of selector elements mounted therein normally arranged to lock the two sections together, means for operating said elements in a predetermined combination to release the two sections for relative movement, a device operable to permit a limited relative movement between the two sections including a pin mounted in one section and a slot in the other section, said pin having a part thereon slidable axially through one section and having a seat in the other section, and said part when moved into said seat being adapted to position the two sections in their normal relation.

25 12. In a controller of the character described, a drum formed in two sections and having a plurality of selector elements mounted therein normally arranged to lock the two sections together, means for operating said elements in a predetermined combination to release the two sections for relative movement, a pin mounted in one section and a slot in the other section, said pin having a part thereon slidable axially through one section and having a seat in the other sec-

30 tion, a spring acting upon said part tending to move it into engagement with its seat whereby to position the two sections in their normal relation, and means operating at a predetermined point in the rotation of the drum for moving said part out of its seat whereby to permit relative rotation between the two sections of the drum to an extent determined by the length of said slot.

35 13. In a controller of the class described, a drum composed of two sections and having a plurality of pins arranged in circular series, said pins being also formed in two sections and certain of the pins normally having their dividing lines offset with respect to the dividing line between the two sections, and the other pins normally having their dividing lines coinciding with the line between the two sections, means operable in the rotation of the drum to move the first mentioned group of pins so as to position their dividing lines between the two sections and thereby release the two sections to relative movement, and a control device operable in such relative movement between the two sections.

40 14. A controller of the class described comprising, in combination, a pair of disks having a plurality of selector elements certain of which operate to hold the disks normally against relative rotation and certain of which normally permit relative rotation, means for rotating said disks, signal-responsive means adapted in the rotation of the disks to move those pins normally locking the disks together into non-holding relation to the disks to release the latter for relative rotation, and a control device operable by such relative movement between the disks.

45 15. A controller of the character described comprising, in combination, a rotary device, a plurality of selector elements carried by said device for rotation therewith, means for rotating said device through a given cycle, means operable by energy derived from the rotation of the device and including a selectively movable part adapted to set said elements in a predetermined combination and a control device operable only upon the selection of said combination.

50 16. A controller of the character described comprising, in combination, a rotary device, a plurality of pins carried by said device for rotation therewith, means for rotating said device through a given cycle, means selectively operable in the rotation of the device to operate a predetermined combination of said pins, said rotary device further comprising a pair of disks normally blocked against relative rotation by certain of said pins, and released for relative rotation when said pins are operated, means acting near the end of each cycle tending to restrain one of said disks to effect such relative movement and a control device operable in such relative rotation between the disks.

55 17. In a controller of the character described, a drum formed in two sections and having a plurality of selector elements mounted therein normally arranged to lock the two sections together, means for operating said elements in a predetermined combination to release the two sections for relative movement, a pin mounted in one section and a slot in the other section, said pin having a part thereon slidable axially through one section and having a seat in the other sec-

60 tion, a spring acting upon said part tending to move it into engagement with its seat whereby to position the two sections in their normal relation, and means operating at a predetermined point in the rotation of the drum for moving said part out of its seat whereby to permit relative rotation between the two sections of the drum to an extent determined by the length of said slot.

65 18. In a controller of the character described, a drum formed in two sections and having a plurality of selector elements mounted therein normally arranged to lock the two sections together, means for operating said elements in a predetermined combination to release the two sections for relative movement, a pin mounted in one section and a slot in the other section, said pin having a part thereon slidable axially through one section and having a seat in the other sec-

70 19. In a controller of the character described, a drum formed in two sections and having a plurality of pins arranged in circular series, said pins being also formed in two sections and certain of the pins normally having their dividing lines offset with respect to the dividing line between the two sections, and the other pins normally having their dividing lines coinciding with the line between the two sections, means operable in the rotation of the drum to move the first mentioned group of pins so as to position their dividing lines between the two sections and thereby release the two sections to relative movement, and a control device operable in such relative movement between the two sections.

75 20. In a controller of the character described, a drum composed of two sections and having a plurality of pins arranged in circular series, said pins being also formed in two sections and certain of the pins normally having their dividing lines offset with respect to the dividing line between the two sections, and the other pins normally having their dividing lines coinciding with the line between the two sections, means operable in the rotation of the drum to move the first mentioned group of pins so as to position their dividing lines between the two sections and thereby release the two sections to relative movement, and a control device operable in such relative movement between the two sections.

80 21. In a controller of the character described, a drum formed in two sections and having a plurality of selector elements mounted therein normally arranged to lock the two sections together, means for operating said elements in a predetermined combination to release the two sections for relative movement, a pin mounted in one section and a slot in the other section, said pin having a part thereon slidable axially through one section and having a seat in the other sec-

85 22. In a controller of the character described, a drum formed in two sections and having a plurality of selector elements mounted therein normally arranged to lock the two sections together, means for operating said elements in a predetermined combination to release the two sections for relative movement, a pin mounted in one section and a slot in the other section, said pin having a part thereon slidable axially through one section and having a seat in the other sec-

90 23. In a controller of the character described, a drum formed in two sections and having a plurality of selector elements mounted therein normally arranged to lock the two sections together, means for operating said elements in a predetermined combination to release the two sections for relative movement, a pin mounted in one section and a slot in the other section, said pin having a part thereon slidable axially through one section and having a seat in the other sec-

95 24. In a controller of the character described, a drum formed in two sections and having a plurality of selector elements mounted therein normally arranged to lock the two sections together, means for operating said elements in a predetermined combination to release the two sections for relative movement, a pin mounted in one section and a slot in the other section, said pin having a part thereon slidable axially through one section and having a seat in the other sec-

100 25. In a controller of the character described, a drum formed in two sections and having a plurality of selector elements mounted therein normally arranged to lock the two sections together, means for operating said elements in a predetermined combination to release the two sections for relative movement, a pin mounted in one section and a slot in the other section, said pin having a part thereon slidable axially through one section and having a seat in the other sec-

105 26. In a controller of the character described, a drum formed in two sections and having a plurality of selector elements mounted therein normally arranged to lock the two sections together, means for operating said elements in a predetermined combination to release the two sections for relative movement, a pin mounted in one section and a slot in the other section, said pin having a part thereon slidable axially through one section and having a seat in the other sec-

110 27. In a controller of the character described, a drum formed in two sections and having a plurality of selector elements mounted therein normally arranged to lock the two sections together, means for operating said elements in a predetermined combination to release the two sections for relative movement, a pin mounted in one section and a slot in the other section, said pin having a part thereon slidable axially through one section and having a seat in the other sec-

115 28. In a controller of the character described, a drum formed in two sections and having a plurality of selector elements mounted therein normally arranged to lock the two sections together, means for operating said elements in a predetermined combination to release the two sections for relative movement, a pin mounted in one section and a slot in the other section, said pin having a part thereon slidable axially through one section and having a seat in the other sec-

120 29. In a controller of the character described, a drum formed in two sections and having a plurality of selector elements mounted therein normally arranged to lock the two sections together, means for operating said elements in a predetermined combination to release the two sections for relative movement, a pin mounted in one section and a slot in the other section, said pin having a part thereon slidable axially through one section and having a seat in the other sec-

125 30. In a controller of the character described, a drum formed in two sections and having a plurality of selector elements mounted therein normally arranged to lock the two sections together, means for operating said elements in a predetermined combination to release the two sections for relative movement, a pin mounted in one section and a slot in the other section, said pin having a part thereon slidable axially through one section and having a seat in the other sec-

130 31. In a controller of the character described, a drum formed in two sections and having a plurality of selector elements mounted therein normally arranged to lock the two sections together, means for operating said elements in a predetermined combination to release the two sections for relative movement, a pin mounted in one section and a slot in the other section, said pin having a part thereon slidable axially through one section and having a seat in the other sec-

17. A controller of the class described comprising, in combination, a pair of disks having sectional pins normally locking them together, signal responsive means arranged to operate said pins whereby to release the disks to relative rotation, means for causing one of the disks to move relative to the other when thus released, and a control device operable in the relative movement between the disks.

18. A controller having, in combination, a rotary device comprising a pair of disks, selector elements mounted for longitudinal movement relative to the disks and normally locking the disks for rotation together, said elements being adapted when positioned in accordance with a predetermined combination to release the two disks for relative rotation, and means operating at a predetermined point in the rotation of the disks to restore them to their normal relation.

19. A controller having, in combination, a rotary device comprising a pair of disks, selector elements mounted for longitudinal movement relative to the disks and normally locking said disks for rotation together, said elements being adapted when positioned in accordance with a predetermined combination to release the two disks for relative rotation, means operating to effect such relative rotation, means subsequently operating to restore the disks to their normal relation, and means for resetting the elements when such normal relation has been restored.

20. The combination of a carrier having two parts, a set of movable elements normally operating to hold the parts together and a set of movable elements normally permitting movement of one of the parts, the first set of elements being movable into positions whereby to release the connection between the parts and the second set of elements being adapted when moved to lock the parts together, and signal-responsive means adapted to operate the first set of elements only upon receipt of the predetermined signal combination.

21. In an apparatus of the character described, the combination of a controller having a series of selector elements and arranged to operate through a predetermined cycle, means adapted to operate a predetermined combination of said elements during such operating cycle including a receiver having a detector tube, and electromagnetically controlled means for operating said selector elements, said tube including a grid, and means operating periodically to discharge the accumulation of negative potential on the grid.

22. A selective signaling apparatus having, in combination, two members mounted for relative rotation, one of said members having a series of elements with which the other member is operatively associated successively, and signal-responsive control means including a detector tube with electromagnetic

means in the output circuit thereof, and means operating to discharge the grid of the tube at a predetermined time after the association of the one member with each of the elements of the other member.

23. The combination of a controller having a series of selector elements and operable through a predetermined cycle, and signal-responsive means for operating said elements in a predetermined combination including an operating member with which said elements are adapted to engage successively, electromagnetic means for controlling said member, means responsive to successive fields of radiant energy adapted to operate said electromagnetic means and including a three element detector tube having a grid, and means for discharging the grid after the engagement of each of said selector elements with the operating member.

24. In a signaling apparatus, the combination of a controller having a series of selector elements, an operating member to which said elements are presented in succession, signal-responsive means for controlling said operating member including a detector tube having a cathode and a controlling element, electromagnetic means in the output circuit of said tube, and means for periodically connecting the controlling element of the tube to a point whose potential is approximately equal to the potential of the cathode or positive thereto.

25. In a signaling apparatus, the combination of a controller having a series of selector elements, an operating member to which said elements are presented in succession, signal-responsive means for controlling said operating member including a detector tube having a cathode and a controlling element, electromagnetic means in the output circuit of said tube, and means for periodically connecting the controlling circuit of the tube to a point whose potential is approximately equal to the potential of the cathode or positive thereto including a switch, and a rotary element operating synchronously with said controller whereby to operate said switch.

26. The combination of a controller having a series of selector elements arranged in a predetermined spaced relation with the elements near the end of the series spaced a greater distance apart than the elements at the beginning of the series, signal-responsive means including a detector tube having a controlling circuit and a controlled circuit, and means periodically connecting the controlling circuit to a point whose potential is approximately equal to the potential of the cathode of the tube or positive thereto including a rotary device and a switch, said device having means for operating said switch spaced substantially in accordance with the spacing of said selector elements.

27. In a signaling apparatus, the combination of a controller having a series of selector

elements and an operating device, means operating to effect engagement between said elements and said device in succession, and means for controlling said operating device including a detector tube having a grid and a device for periodically discharging the grid including a switch and a series of elements arranged to operate the switch successively, the selector elements near the end of the series being spaced a greater distance apart than the elements at the beginning of the series, and the switch operating elements being correspondingly spaced apart.

28. In a signaling apparatus, the combination of a controller having a series of independently movable selector elements and a device operable upon said elements selectively to set the same in a predetermined combination, signal-responsive means for controlling said device, and means for controlling the signal-responsive means including a second series of relatively fixed elements and a pair of switch contacts controlled thereby, the elements near one end of each of the series being spaced a greater distance apart than the elements at the other end of each of the series.

29. The combination of a series of selecting elements and a carrier therefor, a member arranged to operate upon said elements successively, means for operating the carrier to present said elements to said member successively including a motor, a normally open circuit for supplying electric energy to said motor, electromagnetic means for closing said circuit, and means also operated by said electromagnetic means for controlling said member to effect a setting of said elements selectively in a predetermined combination.

40 30. In a selective signaling apparatus, the combination of a series of selector elements and a rotary carrier therefor, a member to operate upon said elements successively, signal-responsive means for controlling said member including a detector tube having electromagnetic means in the output circuit thereof, means for rotating the carrier including a motor, a circuit for supplying energy to the motor and having a switch operable at a predetermined point in the rotation of the carrier to open said circuit, and means for preventing the accumulation of potential on the grid of said tube during the opening of said circuit by the switch.

55 31. In a selective signaling apparatus, the combination of a series of selector elements and a rotary carrier therefor, a member to operate upon said elements successively, signal-responsive means for controlling said member including a detector tube having electromagnetic means in the controlled circuit thereof, means for rotating the carrier including a motor, a circuit for supplying energy to the motor and having a switch operable at a predetermined point in the rotation of

the carrier to open said circuit, and means for connecting the controlling circuit of the tube to a point whose potential is approximately equal to that of the cathode of the tube or positive thereto during the opening of said switch.

32. In a selective signaling apparatus, the combination of a series of selector elements and a carrier therefor, a member arranged to operate upon said elements successively, signal-responsive means for controlling said member including a detector tube, the detector tube having a controlling circuit and a controlled circuit, electromagnetic means in the output circuit of the tube for operating said member, means for periodically connecting the controlling circuit to the ground once for each of said elements whereby to discharge the tube, means for driving said carrier including an electromagnetic motor, and a circuit for supplying energy to said motor having a switch arranged to be opened after a predetermined operating cycle of the carrier, the means for discharging the tube being effective during the opening of said switch but ineffective after the opening of said switch.

33. In a selective signaling apparatus combination of a member arranged to rotate through successive cycles, means for driving said member including an electromagnetic motor, a circuit for supplying energy to said motor and having a switch adapted to be opened at the end of each operating cycle, signal-responsive means operating in the rotation of said member and including a detector tube having a grid and means for discharging the grid during the opening of said switch, and means for rendering said discharge means ineffective after the opening of said switch, whereby to restore the grid to a receptive condition for the next cycle of operation.

34. A selective receiver of the start-stop type comprising, in combination with a plurality of selector elements, means for controlling the operation of said elements including an operating part arranged for association successively with said elements and a signal-responsive part for controlling the operating part, said signal-responsive part including means operable to receive a signal unit, and controlling means for the last mentioned means operating in advance of the association with the operating part of the selector element to be controlled by said unit and adapted to retain the character of said unit until said operating part becomes effective to operate said selector element.

35. A selective receiver of the start-stop type comprising, in combination with a plurality of selector elements, means for controlling the operation of said elements including an operating part arranged for association successively with said elements and a signal-responsive part for controlling the

- operating part, said signal-responsive part including a detector tube having a grid serving to retain the character of a given signal unit, and means for discharging the grid to terminate the period of control by said unit.
36. In a selective signalling apparatus, the combination of a receiver having a selector operable through a predetermined cycle and having a series of elements to be operated selectively under the control of a received signal combination, means responsive to the signal units and adapted for periodic operation with respect to said elements, each operating cycle of the selector being divided into a plurality of control periods, and means controlled by the operation of the selector for governing said signal responsive means so as to determine the effective duration of each of said control periods.
37. A selective receiver of the start-stop type comprising, in combination with a plurality of spaced elements, means for distributing the units of a received signal combination to said elements including an operating part arranged for association successively with said elements and a signal-responsive part for controlling the operating part, said signal responsive part including an electro-magnet, and means operating during the association of any one selector element with said operating part to condition the magnet for the succeeding signal unit.
38. A selective receiver of the start-stop type comprising, in combination with a plurality of selector elements, means for controlling the operation of said elements including an operating part arranged for association successively with said elements and a signal-responsive part for controlling the operating part, said signal responsive part including a detector tube circuit having an electromagnet therein, and means operating in advance of the association of a selector element with said operating part to discharge the detector tube whereby to condition the magnet for the succeeding signal unit.
39. A selective receiver comprising a series of selector elements, signal responsive means to be operated in a predetermined combination to set said elements selectively, and means for detecting the setting of said elements in a predetermined combination comprising a member controlled by said elements, and means including a yieldable stop for actuating said member when said elements have been set in the predetermined combination.
40. A selective receiver comprising, in combination, a series of selector elements, signal-responsive means adapted to operate said selector elements in a predetermined combination, a pair of members movable conjointly with said elements and adapted for relative movement only when the predetermined combination has been selected, and a device operable as an incident to such relative movement between said members.
41. A selective receiver comprising, in combination, a series of selector elements, signal-responsive means adapted to set said selector elements in a predetermined combination, a device to be operated, and a pair of members adapted for relative movement only upon the setting of said elements in the predetermined combination, said device including a pair of yieldable stops, and means on said pair of members for engaging the respective stops to operate said device in the changed positions of said pair of members.
42. In a signaling apparatus, the combination of a rotary device, driving means therefor, a plurality of movable selector elements carried by said device for rotation therewith, an electromagnet, and means including a selectively movable part operating under the control of the magnet by energy derived solely from the motion of said driving means to operate said selector elements selectively.
43. A selector for a signaling system comprising, in combination, a plurality of selector elements arranged in parallel relation for bodily movement and also for individual movement into either of two set positions, a pusher device normally disposed in the path of the elements successively presented thereto and adapted by engagement with each element to shift it out of normal set position or to yield and allow the element to pass unpushed, a control element movable into and out of blocking relation with said pusher, and a member adapted to be controlled in its movements by the setting of said elements by said pusher device.
44. In a selective receiver, the combination of a series of selector elements, a yieldable member, means for effecting a movement of translation between said elements and said member, and signal responsive means operative to hold said member in a position to move said elements in the operation of said translating means.
45. A selector mechanism having, in combination, a rotary device comprising a pair of disks, a series of selector elements for controlling the relative angular positions of said disks and normally locking the disks together, signal-responsive means for operating said elements in a predetermined combination whereby to permit a change in the relative positions of the disks, and a means to be operated controlled by such change in the positions of the disks.
46. A selective signal receiver having, in combination, a series of selector elements, a pair of members normally locked against relative movement by said elements and movable conjointly with said elements through a signal cycle, the relative positions of said members being controlled by the positions of

- said elements, and means responsive to a change in the positions of said two members as permitted by said elements.
47. A selector for a signaling system comprising, in combination, a plurality of selector elements supported for bodily movement transversely of their lengths and also for individual adjustment, signal responsive means controlling said adjustment, a member 10 movable conjointly with said elements and adapted for movement independently of said elements when the elements are set in a predetermined combination, and a device to be operated responsive to said independent 15 movement of the member.
48. A selective receiver having, in combination, a series of selector elements, a pair of members controlled by said elements, a signal-responsive device, means for effecting 20 a movement of translation between said elements and said device through a predetermined operating cycle, said elements being adapted when operated in a predetermined combination to permit a change in the relative 25 positions of the two members, a device to be operated responsive to said change in the positions of the two members, and means operating at the end of each operating cycle to reset said two members in their normal 30 relative positions.
49. A selective receiver having, in combination, a series of selector elements, a pair of members movable with said elements, a signal-responsive device, means for effecting 35 a movement of translation between said elements and said device through a predetermined operating cycle, said elements being adapted when operated in a predetermined combination to permit a change in the relative 40 positions of the two members, and a device to be operated responsive to said change in the positions of the two members, the device to be operated comprising a switch having a pair of contacts, and means on said 45 members for controlling said contacts according to the relative positions of the two members.
50. A selective receiver of the start-stop type comprising a rotary carrier having a 50 series of individually movable selector elements, a signal responsive device, and means for effecting a movement of translation between said device and said selector elements in which said elements are adapted to be 55 operated selectively, said means comprising a vibratory motor, signal-responsive means for starting the motor for operation through a complete cycle, and means operating automatically to continue the operation of the 60 motor and to stop it at the end of said predetermined cycle, said vibratory motor being connected with a source of alternating current and adapted to attain its normal torque and speed substantially instantaneously upon the closing of the motor circuit while 65 maintaining such speed throughout the operating cycle.
51. A selective receiver of the start-stop type comprising an element to be rotated at a substantially uniform speed through one revolution, a vibratory motor for driving said element, a source of alternating current, signal responsive means for connecting said motor with the source of alternating current to start said element, said motor being adapted to attain its normal torque and speed substantially instantaneously and to maintain the speed substantially uniform, and means operating to cut off the supply of current to the motor at the end of the operating cycle to stop the element, the connection between the motor and said source of current comprising a temporary starting circuit adapted to be controlled by said signal-responsive means, and a main circuit controlled by the movement of said element. 70
52. A selective receiver of the start-stop type comprising a series of selector elements and a rotary carrier therefor, signal-responsive means adapted to operate said elements selectively in the rotation of the carrier, an electric motor for rotating the carrier, said signal responsive means including a magnet, a starting circuit controlled by said magnet and adapted to supply electric energy to the motor temporarily to start the same, and a main supply circuit controlled by the rotation of the carrier at the beginning and end of its operating cycle. 75
53. A selective receiver comprising a series of selector elements, signal-responsive means, means for effecting a movement of translation between said elements and said signal-responsive means in which said elements are adapted to be operated selectively under the control of said means, said signal-responsive means including a signal-responsive part and an independently movable operating part, said operating part comprising a yieldable member, and the signal-responsive part including a locking member, said members being adapted to be held in interengaging relation by the engagement of a selector element with the operating part. 80
54. In a signaling apparatus, the combination of a detector tube having a controlled circuit and a controlling circuit, a connection between the controlling circuit and the ground having a switch therein, a selector mechanism comprising a series of selector elements and a signal-responsive device adapted to control the operation of said elements, and means for intermittently operating said switch to control the operation of the signal-responsive device. 85
55. A selective receiver of the start-stop type comprising, in combination, a series of selector elements, a signal responsive device including a detector tube, means including an electric motor for effecting a movement of 90

- translation between said elements and said device through a predetermined cycle, means including a switch for stopping the motor at the end of each cycle, said signal-responsive device being adapted to initiate the operation of the motor and to operate said elements selectively during said operating cycle, and means for momentarily rendering the tube ineffective while the motor switch is being 10 opened at the end of the cycle. 56. A selective receiver of the start-stop type comprising, in combination, a series of selector elements, a signal-responsive device including a detector tube, means for effecting a movement of translation between said elements and said device through a predetermined cycle including an electric motor, means including a switch for stopping the motor at the end of each cycle, said signal- 15 responsive device being adapted to initiate the operation of the motor, and means for discharging the grid of the detector tube during the opening of the motor switch at the end of the cycle. 57. A selective receiver of the start-stop type comprising, in combination, a series of selector elements, a signal responsive device including a detector tube, means for effecting a movement of translation between said 20 elements and said device through a predetermined cycle including an electric motor, means including a switch for stopping the motor at the end of each cycle, said signal- responsive device being adapted to initiate 25 the operation of the motor to start each operating cycle, and means for momentarily rendering the tube ineffective while the motor switch is being opened at the end of the cycle, the last mentioned means comprising a rotary 30 element, a second switch adapted to be closed by said element at the end of the operating cycle, and means operating after the termination of the cycle to open said second switch. 58. In a selective signaling apparatus, the 35 combination of a selector, an electric motor for driving the selector through a predetermined operating cycle, a signal-responsive device including a detector tube operable to initiate the starting of the motor, said 40 motor having a connection with a source of electric energy with a controlling switch adapted to be opened at the end of the operating cycle, and means for rendering the tube ineffective as a detector during the opening 45 of said switch at the end of each operating cycle. 59. In a selective signaling apparatus, the 50 combination of a selector, an electric motor for driving the selector through a predetermined operating cycle, a signal-responsive device including a detector tube operable to 55 initiate the starting of the motor, said motor having a connection with a source of electric energy with a controlling switch therein 60 adapted to be opened at the end of the oper- ating cycle, and means for rendering the tube ineffective during the opening of said switch at the end of each operating cycle, the last mentioned means including a device deriving energy from the operation of the motor to 70 recondition the detector tube immediately upon the opening of said switch. 60. In a selective signaling apparatus, the combination of a selector, an electric motor for driving the selector through a predetermined operating cycle, a signal-responsive device including a detector tube operable to initiate the starting of the motor, said motor having a connection with a source of electric energy with a controlling switch therein 75 adapted to be opened at the end of the operating cycle, and means for rendering the tube ineffective during the opening of said switch at the end of each operating cycle, the last mentioned means including a device controlled by the opening of the switch to recondition the tube. 61. In a selective signaling apparatus, the combination of a selector, an electric motor for driving the selector through a predetermined operating cycle, a signal responsive device including a detector tube operable to initiate the starting of the motor, said motor having a connection with a source of electric energy with a controlling switch therein 80 adapted to be opened at the end of the operating cycle, and means for rendering the tube ineffective during the opening of said switch at the end of each operating cycle, the last mentioned means including a device controlled by the opening of the switch to recondition the tube. 62. A selective receiver having, in combination, a rotary carrier having a series of individually movable selector elements arranged in a circular series, a signal responsive device, driving means for rotating said carrier, means controlled by said signal responsive device for setting said elements, means 85 momentarily operated under the control of said signal responsive device to control said driving means whereby to effect rotation of the carrier through a predetermined operating cycle in which said elements are successively presented to said setting means to be set thereby in a predetermined combination under the control of said signal responsive device and means operating at the end 90 of each cycle to detect the setting of said elements in said predetermined combination. 63. A selective receiver of the start-stop type having, in combination, a carrier having a series of selector elements arranged in a circular series, a signal responsive device, driving means for rotating said carrier including an electric motor adapted to be energized from a source of alternating current of constant frequency and operable at a predetermined constant speed, means controlled 95 100 105 110 115 120 125 130

by said signal responsive device for setting said elements, means momentarily operative under the control of said signal responsive device to start rotation of the carrier by said motor to present said elements successively to said setting means to be set thereby in a predetermined combination under the control of said signal responsive device, and other means for stopping the motor at the end of a predetermined operating cycle.

64. A selective receiver of the start-stop type having, in combination, a carrier having a series of individually movable selector elements, a signal responsive device, driving means for rotating said carrier through a predetermined operating cycle including a vibratory electric motor with means for starting the same, said motor being adapted to attain its normal torque and speed substantially instantaneously, means controlled by said signal responsive device for setting said elements in a predetermined combination in the rotation of said carrier, and means operating at the end of each cycle to detect the setting of said elements in said predetermined combination, said signal responsive device being also adapted to control the motor starting means.

65. A selective receiver comprising a series of selector elements and a rotary carrier therefor, a member arranged to operate upon said elements successively, signal responsive means including a relay for controlling said member, a motor for driving said carrier, and means for supplying energy to said motor including a switch controlled by said relay.

66. A selective receiver comprising, in combination, a plurality of elements, signal responsive means, a distributor arranged for association successively with said elements and operable to transfer thereto selectively the effect of the individual units of a signal combination received by said signal responsive means, and means acting to permit said signal responsive means to receive one unit of a signal while the distributor is acting to transfer the effect of the preceding unit of the combination to one of said elements.

67. In a selective signal receiver, the combination of a plurality of spaced elements to which the individual units of a received signal combination are to be distributed, a distributor, means for effecting relative movement between the distributor and said elements to establish operative association between the distributor and said elements successively, means including a magnet responsive successively to the units of a received signal combination according to the individual character of such units, and means controlled by said magnet and acting to transfer the effect of the individual units to said distributor including automatically acting means operating independently of a

subsequent change in the condition of the magnet and upon the association of said distributor with each of said elements to retain for a predetermined interval thereafter the character of the unit controlling said magnet at the time of such association, whereby to permit the period during which the distributor is controlled in accordance with the character of one single unit to be continued and thereby overlap the period during which said magnet is responding to the succeeding unit.

68. A selective receiver comprising, in combination, a plurality of spaced elements to which the individual units of a received signal combination are to be distributed, said elements being arranged in a circular series, a distributor normally positioned for engagement successively with said elements, the engagement with each of said elements continuing throughout a predetermined angular movement between the elements and the distributor, means responsive to the character of the units of a received signal combination, and means for transferring the effect of the units of the signal to said distributor including means acting throughout the period of engagement between the distributor and any one of said elements to retain the character of the signal unit then controlling the distributor independently of the signal responsive means, whereby the signal responsive means is free to respond to one signal unit while the preceding unit is being distributed.

In testimony whereof, I have hereunto affixed my signature.

HOWARD D. COLMAN.
